INVENTOR.
Charles Zimmerli.
BY *Frederick J. Linke*
HIS ATTORNEY.

UNITED STATES PATENT OFFICE.

CHARLES ZIMMERLI, OF ROCHESTER, NEW YORK.

SELF-RIGHTING DESK SIGN.

1,420,603.

Specification of Letters Patent. Patented June 20, 1922.

Application filed April 13, 1921. Serial No. 461,009.

To all whom it may concern:

Be it known that I, CHARLES ZIMMERLI, a citizen of the United States, residing at Rochester, in the county of Monroe and State of New York, have invented certain new and useful Improvements in Self-Righting Desk Signs; and I do hereby declare the following to be a full, clear, and exact description of the same, reference being had to the accompanying drawings, forming a part of this specification, and to the reference numerals marked thereon.

My present invention relates to card and sign exhibiting, and more particularly to portable signs, such as are used on office desks, counters, etc., to identify persons, goods or departments, and the invention has for its object to provide a simple, neat and attractive sign of this character that will right itself when its equilibrium is disturbed and serve to maintain itself with the card or device which it is intended to display, unobscured. A further object of the invention is to render such a device cheap and economical to manufacture and to these and other ends the invention consists in certain improvements and combinations of parts, all as will be hereinafter more fully described, the novel features being pointed out in the claims at the end of the specification.

In the drawings:

Figure 1 is a side view of a desk sign constructed in accordance with and illustrating one embodiment of my invention;

Figure 2 is an end view thereof;

Figure 3 is a cross section somewhat reduced and illustrating the preferred laminated construction thereof, and

Figure 4 is a perspective view.

Similar reference numerals throughout the several views indicate the same parts.

I prefer to construct the sign or card exhibitor in a solid piece comprising a body portion of prismatic form and substantially triangular in cross section as shown, the base or bottom face being indicated at 1 and the lateral or converging side faces at 2. Each of such side faces carries a sign card 3 and in the present instance these cards are removably and replaceably held in place by offset or overhanging shoulders 4 and 5 at the top and bottom respectively of these faces. The cards are slidably removable from these retaining devices and may be inserted therein endwise of the body.

I prefer to construct the latter of a plurality of pieces, secured together for reasons that I will explain and in the present instance it is formed of three pieces of wood A, B and C glued together or otherwise permanently attached, as best shown in Figure 3. The pieces B and C are progressively smaller and hence naturally lighter than the piece A because of the taper of the block, and I make the pieces A and C, say, of oak or other hard and relatively heavy wood, and the intermediate piece B of a lighter material, such as white wood. This accentuates the disproportionate weight of the base portion A on the one hand and the rest of the block on the other; lowers the center of gravity and causes the sign to always automatically right itself when tipped over on to any face except the base face 1, and to always rest on that face so that both signs 3 will be always in view. For this purpose the base 1 is in the form of a rocker, as shown, created by rounding the sides of the piece A as indicated at 6. Another advantage of the plural construction is that it reduces the cost of manufacture while retaining the desired elegance of finish on the part of the exposed parts (made of the rarer wood) which are the parts A and C, a cheaper wood being used at B.

Still another advantage is that it is easier to provide the retaining shoulders 4 and 5 which may be conveniently formed before the parts A and C are assembled and while they are being shaped by forming grooves 7 therein along each edge, as shown.

To assist the block in righting itself as described, I prefer to provide additional curved rockers 8 at the ends which extend out laterally beyond the sign cards 3 and the faces against which they lie. In the present instance the pair of rockers at each end is formed from a substantially circular piece of wire bent to a curve gradually conforming to and meeting with the curves of the base rocker faces 6. The intermediate portion of the wire has an eye 9 by means of which it is screwed to the top of the end of the body at 10, while the ends 11 are bent at right angles and driven into the body lower down.

It will be noted that the sign cards may be inserted or removed endwise through these rocker members.

I claim as my invention:

1. A self righting desk sign comprising

a prismatic body of substantially triangular cross section, said body being weighted upon its base face, and one of the other converging faces being provided with means for retaining and displaying a sign card.

2. A self righting desk sign comprising a prismatic body of substantially triangular cross section made in three separate pieces secured together, the base and the apex portions being composed of relatively heavier material than the intermediate portion.

3. A self righting desk sign comprising a prismatic body of substantially triangular cross section made in three separate pieces secured together, the base and the apex portions being composed of relatively heavier material than the intermediate portion and being provided with grooved shoulders whereby they are adapted to jointly retain and display a sign card.

4. A self righting desk sign comprising a prismatic body of substantially triangular cross section made in a plurality of separate pieces secured together, the base portion being composed of relatively heavier material than the next adjacent portion, and means for retaining and displaying a sign card on one of the lateral faces of the body.

5. A self righting desk sign comprising a prismatic body of substantially triangular cross section, said body being weighted upon its base face constituting its bottom and being provided with pairs of offset retaining flanges on each of its lateral faces, each such

pair of flanges being adapted to receive and retain a sign card inserted therein endwise of the body.

6. A self righting desk sign comprising a prismatic body of substantially triangular cross section, said body being weighted on its base face constituting its bottom and provided with curved laterally extending rockers at each end, and means on the lateral faces of the body for retaining and displaying sign cards.

7. A self righting desk sign comprising a prismatic body of substantially triangular cross section, said body being weighted on its base face constituting its bottom and provided with curved laterally extending rockers at each end, and means on the lateral faces of the body for retaining and displaying sign cards insertable and removable endwise through the rockers.

8. A self righting desk sign comprising a prismatic body of substantially triangular cross section, said body being weighted on its base face constituting its bottom and provided with curved laterally extending rockers at each end, and means on the lateral faces of the body for retaining and displaying sign cards, said rockers embodying substantially circular wires having their intermediate portions and their end portions anchored in the respective end faces of the body.

CHARLES ZIMMERLI.
